CLAIM

The ornamental design for a portable pressing board, substantially as shown and described.

DESCRIPTION

FIG. 1 is a side elevational view of a portable pressing board showing my new design, the opposite side elevational view being a mirror image thereof.

FIG. 2 is a front elevational view thereof.

FIG. 3 is a rear elevational view thereof.

FIG. 4 is a top plan view thereof.

FIG. 5 is a bottom plan view thereof.
